UNITED STATES PATENT OFFICE.

ALVIN C. GODDARD, OF RICHMOND HILL, NEW YORK.

PIVOT HINGE.

Application filed August 9, 1927. Serial No. 211,652.

My invention relates to hinges, and particularly to pivot hinges of the type adapted to the support of swinging transoms.

My invention has for its object the provision of a hinge, adapted for use with transoms, French doors, pivoted windows, and such like constructions, in which is included a friction device for retarding the free swinging of the transom or window, so that the latter may be conveniently positioned at a given amount of opening, and will not be susceptible of movement by puffs of air or other minor forces when so positioned. My invention provides a friction device which is incorporated within a pivot hinge of minimum size, which is readily adjustable, which retains its adjustment over a prolonged period of time, and which is simple to make, and noiseless in operation. The device of my invention is easy to install, and when installed has a long life. It is particularly adapted to use in such locations as the windows of hospitals, schools, libraries and hotels, since it is noiseless in operation. It is further particularly desirable, because the window, which is supported by it, may be opened to any desired degree, for any desired amount of ventilation, and when so opened will remain in any adjusted position, as distinguished from the customary click controlled or chain held transoms. My invention further provides a friction brake mechanism which is separate and distinct from the journal bearing surfaces carrying the weight of the window member, distinguishing thereby from devices of the prior art intended for similar purposes. My device likewise provides means for the adjustment of the friction pressure, which are readily accessible, but are concealed against disturbance by the casual user.

By the device of my invention I am thus enabled to provide a simple, durable, convenient pivot hinge adapted to the support of transoms and such like devices, which is simple to construct, simple to adjust, easy to install, and durable in operation.

Other objects and structural details of my invention will be apparent from the following description when read in connection with the accompanying drawings, wherein:

Fig. 1 is a view of the device of my invention installed in a transom window having stop members;

Fig. 2 is a similar view of the same embodiment installed in a transom having no stops;

Fig. 3 is a side view of my device from the mortise side;

Fig. 4 is a side view of the same embodiment from the flush side showing the friction plate member;

Fig. 5 is a view in longitudinal section of the same embodiment, and

Fig. 6 is a view in transverse section of the same embodiment.

Referring to the figures, I provide a base plate member 1 which is desirably strengthened by means such as ribs 2 which may be formed by bending the metal of the plate, and which is desirably equipped with end closures 3. Screw holes 4 are likewise desirably provided through the metal in convenient places for the attachment of the device to the window member. Cooperating with the base plate 1 is a second plate member 5, which likewise is formed with strengthening members 6, desirably formed by folding the edges of the plate, and also with end closures 7. The plate 5 may desirably be approximately equal in width to the plate 1, and is desirably sufficiently shorter than plate 1 to permit of the end closures 7 swinging freely within the end closures 3. At the center of the plate 1 a boss 8 having a concentric opening 9 therethrough is formed as shown. The boss 8 is struck forward towards the plate member 5, which also is provided with an opening 11 adapted to register coaxially with the opening 9. A friction plate 12 is provided positioned adjacent the plate member 5, between the end closures 7, and adapted to float freely within the space formed between the end closures 7 and the side ribs 6. The friction plate 12 is drilled and tapped for screws 14 which serve to position the friction plate relatively to the plate 5 by reason of the heads of the screws contacting with plate 5. This plate has apertures 14 formed therein and directly over the screw heads but of smaller diameter whereby access may be had to the screws for purpose of adjustment.

A pivot member 15 is provided, passing through the openings 9 and 11, with the smaller end 16 desirably riveted, or otherwise fastened, to the plate 1 in such way that it does not rotate. Screw holes 17 are provided through the plate 5 and the plate 12. A third opening 18 is provided through the friction plate 12, which is desirably tapered. The pivot member 15 likewise is desirably tapered at its projecting end, to match the taper in

the hole 18 in the friction plate 12. The opening 11 desirably makes a smooth journal fit with the pivot 15, so as to permit of free movement thereon.

5 The construction of my device thus provides a frame member 1 adapted to be fastened to a portion of a window or door, while the plate 5 is adapted to be fastened to another portion of the door, the respective members being fastened interchangeably to the door or window frame and to the door or window casing, since the device of my invention works equally well in either position. When so positioned, the weight of the frame is carried upon screws through the appropriate openings 4 and 17. If the plate 1 is fastened to the casing and the plate 5 to the window frame, the weight of the window is transferred to the plate 5, and is carried by the 10 journal bearing in the opening 11, upon the pivot 15, which in turn is carried by the plate 1 and the window casing. The weight of the window is thus carried freely upon the pivot, and it is free to swing into any desired 15 position.

20 After being properly installed, the desired amount of frictional retardation may be imposed upon the swinging member by adjustment of the friction plate 12, this being accomplished by movement of the screws 14. These screws may be turned to the left and thereby force the tapered surface of the opening in the plate 12 against the tapered portion of the pivot 15, and the plate 5 against 25 the boss 8 in the plate 1. The desired amount of friction then occurs, divided between the surface of the boss 8 in contact with the plate 5, and the tapered surfaces upon the pivot 15 and the opening in the plate 12. By this 30 construction the friction is very easily adjusted to any desired value, from an amount so great that vigorous muscular effort is required to move the supported window, to an amount which is imperceptible.

35 The pivot 15 is desirably made of brass, and the plate 12 is desirably made of iron, such as cold rolled steel, thereby reducing the wear which occurs after prolonged service. The journal 11 and the face of the boss 8 may, 40 if desired, be lubricated, although such lubrication is not essential either to the operation or long life of the device of my invention. The construction as disclosed is adapted to easy adjustment, to permanent retention of 45 adjustment, and to long continued service without readjustment. When, however, wear occurs, as is inevitable with any moving object, and the amount of friction falls to an undesirably low value, readjustment is readily and conveniently made by further movement of the screws 14. Or if the requirements 50 of service upon the window change, and more, or less, friction is desired, readjustment is readily made, again by movement of the 55 screws 14 in the appropriate direction.

It is, of course, desirable that a pair of such pivot hinges be used, one on each side of the transom or window. In the embodiment shown, the pivots are indicated as utilized for the support of a transom, swinging upon a horizontal axis. They are, however, equally applicable to other windows, such as French windows, swinging upon a vertical axis.

50 The pivot hinge of my device is particularly easy to install, since it requires the cutting of but a single mortise. The mortise may be cut within the frame of the transom, or within the casing or casement in which it is mounted. It is, however, preferable that the mortise be cut within the transom or window frame, since the device is adapted to be made in a width similar to the standard width of window frames, and the mortise is accordingly readily made by the use of saw and chisel. For purposes of high grade workmanship, 55 the ends of the mortises may be rounded to fit the curved closures 3, by means of a curved chisel. This is not, however, necessary since many other ways of fitting the pivot hinge to the window are available. It is, of course, 60 desirable that the member 1 be fitted within the mortise to avoid the necessity for rubbing friction between the closures 3 and the frame. The hinge of my invention is equally well 65 adapted to use with windows which have or do not have stops, and the method of adjustment thereto will be obvious to one skilled in the art, as shown in Figs. 1 and 2.

70 By the device of my invention I am thus enabled to produce a highly satisfactory, easily installed, durable, and inexpensive hinge adapted to a wide variety of uses, which will be obvious to one skilled in the art.

75 While I have shown and described but a single embodiment of the device of my invention in the accompanying figures and description, it is capable of various modifications therefrom without departing from the spirit thereof, and I desire, therefore, that only such limitations shall be imposed upon the 80 claims hereafter appended as are required by the prior art.

85 I claim as my invention:

1. A hinge device comprising in combination, a pair of frame plates in frictional engagement with each other, a pivot forming a bearing to permit one to turn with respect to the other, a floating friction plate member and means coacting therewith to increase the pressure between said frame plates.

125 2. A hinge device comprising in combination, a pair of frame plate members having median openings, a pin positioned within said openings, attached therein to one of said plates, and forming a journal bearing for the other thereof, and having a conical portion, a friction plate member floating within one of said frame members, having a median tapered opening cooperating with the tapered portion of said pin, and means comprising 130

pressure screws cooperating between said friction plate and said frame member to produce pressure, and thereby friction between the conical members.

- 5 3. A hinge device comprising a pair of frame plates having openings therein, one of said plates having a boss portion formed around said opening, a pivot member fastened in the opening of one of said frame plates and 10 forming a journal bearing for the other frame plate, a friction surface on said pivot, and means comprising a member frictionally engaging with said pivot friction surface for the application of pressure between said frames 15 for producing friction between one of the frame plates and said boss.

4. A hinge comprising frame members, a cooperating pivot member, and a floating friction bar member cooperating with said 20 pivot for the development of an adjusted amount of frictional retardation, and means comprising pressure screws cooperating with said friction bar for adjusting said friction member relatively to said pivot to vary the degree of said friction.

5. A hinge comprising a pair of rectangular frame members having stiffening portions, openings therethrough for attachment to cooperating window and casing members, a 30 pivot member attached to one thereof and cooperating with the other thereof, a floating friction member enclosed within one of said frames, and cooperating with said pivot member, and means comprising pressure screws cooperating between said friction bar and said frame for the adjustment of frictional retardation.

6. A hinge comprising a pair of flat plates having median openings with axes perpendicular to the plane of said plates, strengthening 40 and guard means cooperating therewith, a pivot member attached in the opening in one of said frames and cooperating with the opening in the other thereof to form a journal bearing therefor, the axis of said pivot being perpendicular to the plane of said frames, a floating friction member positioned between said strengthening members, and cooperating with said pivot, and means comprising pressure screws for the development of an ad-

justed amount of frictional retardation therebetween.

7. In a pivot hinge, a friction member, a friction member pivoted thereto and in frictional engagement therewith and threaded means applied to one of said members at a plurality of points eccentric to its pivot for increasing its pressure upon the other member.

8. In a pivot hinge, a friction member, a pivot upon which said member is mounted, a friction surface on said pivot, a second member on said pivot, and threaded means coacting with said pivot friction surface and with the second member to increase its pressure upon the first member.

9. In a pivot hinge, a friction member, a pivot member associated therewith, a second friction member on said pivot member, said pivot member having a conical surface, a 70 plate having a conical surface in engagement therewith, and threaded means coacting directly with said second friction member and said plate to force them apart.

10. In a pivot hinge, a friction member, a pivot member associated therewith, a second friction members on said pivot member, said pivot member having a conical surface, a plate having a conical surface in engagement therewith, threaded means coacting directly 80 with said second friction member and said plate to force them apart and means for restraining said plate against rotation with respect to the second friction member.

11. In a pivot hinge, a pin having a friction surface, a pair of friction members associated with said pin, and a third member in engagement with said friction surface and having means for causing pressure between said friction members.

12. In a pivot hinge, a pin having a friction surface, a pair of friction members associated with said pin, and a third member in engagement with said friction surface and having means for causing pressure between said friction members and between the third member and said friction surface.

In witness whereof, I hereunto subscribe my signature.

ALVIN C. GODDARD.
